UNITED STATES PATENT OFFICE.

WARREN E. CAREY, OF TROY, OHIO.

PUMP.

1,198,106.

Specification of Letters Patent. Patented Sept. 12, 1916.

Application filed February 26, 1916. Serial No. 80,709.

To all whom it may concern:

Be it known that I, WARREN E. CAREY, a citizen of the United States, residing at Troy, in the county of Miami and State of Ohio, have invented a new and useful Pump, of which the following is a specification.

The device forming the subject matter of this application is a pump of that general type which embodies a plunger mounted to 10 rotate and to move endwise, the endwise movement of the plunger effecting the pumping operation and the rotation of the plunger serving to close the inlet and outlet ports.

15 The invention aims to provide novel means whereby an endwise movement in opposite directions may be imparted to the plunger, by the use of cams, thereby avoiding the use of springs for imparting a longitudinal movement to the plunger in either direction.

20 Another object of the invention is to increase the capacity of the pump, by so constructing the same that both ends of the plunger will be effective.

25 It is within the province of the disclosure to provide novel means whereby the actuating cams for the plunger may be adjusted circumferentially, thereby to enable the cams 30 to impart properly to the plunger, a longitudinal reciprocating movement.

35 It is within the scope of the disclosure to improve generally and to enhance the utility of devices of that type to which the present invention appertains.

40 With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without 45 departing from the spirit of the invention.

50 In the accompanying drawings: Figure 1 shows in side elevation, a pump embodying one form of the invention; Fig. 2 is an elevation wherein the pump is viewed at right angles to the showing of Fig. 1; Figs. 3 and 4 are longitudinal sections wherein sundry parts appear in elevation, the cutting planes in Figs. 3 and 4 being at right angles to 55 each other; Fig. 5 is a fragmental cross section on the line 5—5 of Fig. 2; Fig. 6 is a

view similar to Fig. 1 but showing a slight modification.

The device forming the subject matter of this application may be variously constructed without jeopardizing the utility of the invention, and a skilled mechanic having before him the showing of the drawings and the following description may make divers departures without rendering the device useless or inoperative. Bearing in mind that large latitude is desired as to structural details, there is shown in the drawings, by way of illustration, a base 1 into which projects the lower end of a cylinder 2 having a longitudinal slot 3 located above the base. In one side face of the base 1 there is a recess 4 adapted to receive the head 5 of a set screw 6 passing through the wall of the cylinder 2 and constituting a means for holding the cylinder in place on the base. The set screw 5 engages a bearing 7 inserted into what may be denominated the lower end of the cylinder 2 assuming, as is not obligatory, that the cylinder 2 is vertically disposed. By loosening the screw 6, the bearing 7 may be adjusted circumferentially, the reason for adjusting the bearing 7 circumferentially being more clearly understood when the entire construction of the device is comprehended. The bearing 7 is provided with a central recess 8 defining a marginal flange 9, the upper edge of which is shaped to form a cam 10. Inserted into the upper end of the cylinder 2 is a bearing 11 having a cap 12 which overhangs the upper end of the cylinder 2, the bearing 11 being held in place by a set screw 14 threaded into the cylinder. The bearing 11 has a central recess 15 defining a marginal flange 16, the lower edge of which is shaped into a cam 17. Intermediate its ends, the cylinder 2 is supplied with an inlet 18 and with an outlet 19.

55 Mounted to rotate and to move endwise in the cylinder 2 and conforming closely to the bore of the cylinder is a plunger 20 having a spiral gear 21 which is accessible through the slot 3 in the cylinder 2. The upper end of the plunger 20 is provided, at one side, with a trough-shaped lip 22 having a longitudinal channel 23, the lip being rounded at its upper end as shown at 24, to coöperate with the cam 17. The lower end of the plunger 20 is provided with a similar lip 25 rounded as shown at 26 to coöperate with the cam 10.

Mounted on or formed integrally with the base 1 is a bearing 27 in which is journaled for rotation a shaft 28, the bearing 27 carrying an oil cup 29 constituting means 5 for lubricating the shaft. Secured to the shaft is a worm wheel 30 which, entering the slot 3 in the cylinder 1, meshes into the spiral gear 21 on the plunger 20 and constitutes a means for rotating the plunger. 10 No especial emphasis is laid on the bearing 27, the shaft 28, the worm wheel 30 and the spiral gear 21, since many mechanical equivalents may be substituted for these elements, it being necessary merely that some efficient 15 means be provided for rotating the plunger 20. When the plunger 20 is rotated, the lip 22 covers the outlet 19 and is in open relation to the inlet 18. Liquid thereupon passes through the inlet 18 into the cylinder 2. A continued rotation of the plunger 20 causes the lip 22 to cover the inlet 18 and to uncover the outlet 19. When the plunger 20 is rotated, the rounded end 26 of the lip 25, coöperating with the cam 10 25 raises the plunger 20 and forces the liquid out of the outlet 19. A continued rotation of the plunger 20 causes the rounded end 24 of the lip 22 to coöperate with the cam 17, whereupon the plunger 20 will be positively 30 forced in a downward direction. It is to be observed that by the construction above outlined, no springs are necessary and, further, the device is quite devoid of movable valves. 35 In Fig. 6 of the drawings, a slight modification of the invention has been shown. In the said figure, parts previously described are designated by reference numerals hereinbefore used with the suffix "a." The 40 only modification in this form of the invention consists in providing an additional inlet 31 and an additional outlet 32, the inlet and the outlet coöperating with the lower end of the plunger 20, so that the capacity 45 of the pump is doubled. The screws 14 and 6 may be loosened at any time to permit a circumferential adjustment of the upper thrust bearing 11 and to permit a circumferential adjustment of the lower thrust bearing 7, to the end that the cams 17 and 50 10 may be set properly with respect to each other.

Whatever means is provided for rotating the plunger, proper provision of course 55 must be made for the longitudinal reciprocation of the plunger. The pump works

equally well, no matter in which direction the plunger is rotated. When the direction of rotation of the plunger is reversed, the direction of flow of the liquid is reversed 60 also.

Having thus described the invention, what is claimed is:—

1. In a pump, a cylinder having inlet and outlet ports; a plunger mounted to rotate and to move endwise in the cylinder, the plunger having at one end a lip controlling the ports when the plunger is rotated; cams in the cylinder, the cams coöperating respectively with the lip and with the other 70 end of the plunger to impart positive endwise movement to the plunger in opposite directions when the plunger is rotated; and means for rotating the plunger.

2. In a pump, a cylinder having inlet and 75 outlet ports; a plunger mounted to rotate and to move endwise in the cylinder, the plunger having at one end a lip controlling the ports when the plunger is rotated; circumferentially adjustable cams in the cylinder, the cams coöperating respectively with the lip and with the other end of the plunger to impart endwise movement to the plunger when the plunger is rotated; means for holding the cams in adjusted positions; and 80 means for rotating the plunger.

3. In a pump, a cylinder having an inlet port and an outlet port adjacent one end and provided with an inlet port and with an outlet port adjacent its other end; a plunger mounted to rotate and to move endwise in the cylinder, the plunger having at its ends lips controlling respectively the inlet and the outlet port adjacent one end of the cylinder, and the inlet and the outlet port 95 adjacent the other end of the cylinder, when the plunger is rotated; abutments in the ends of the cylinder, the abutments and the lips constituting coöperating parts, one of which coöperating parts is provided with a 100 cam, the cams constituting means for imparting an endwise movement to the plunger when the plunger is rotated; and means for rotating the plunger.

In testimony that I claim the foregoing as 105 my own, I have hereto affixed my signature in the presence of two witnesses.

WARREN E. CAREY.
